(57) **CLAIM**

The ornamental design for a battery adapter as shown and described.

DESCRIPTION

FIG. 1 is a front, right, and top perspective view of a battery adapter in accordance with our new design;

FIG. 2 is a rear, left, and bottom perspective view of the battery adapter in accordance with our new design;

FIG. 3 is a front elevational view of the battery adapter in accordance with our new design;

FIG. 4 is a rear elevational view of the battery adapter in accordance with our new design;

FIG. 5 is a top plan view of the battery adapter in accordance with our new design;

FIG. 6 is a bottom plan view of the battery adapter in accordance with our new design;

FIG. 7 is a left side elevational view of the battery adapter in accordance with our new design;

FIG. 8 is a right side elevational view of the battery adapter in accordance with our new design; and,

FIG. 9 is a rear, right, and top perspective view of the battery adapter in accordance with our new design illustrating a state in which the battery adapter is attached to environmental structures (a battery, a power tool adapter attached to a power tool, and a cable connecting the battery adapter and the power tool adapter).

The broken lines in the drawings illustrate the environmental structures or portions of the battery adapter which form no part of the claimed design.
